UNITED STATES PATENT OFFICE.

JAMES S. ATTERBURY AND THOMAS B. ATTERBURY, OF PITTSBURG, PA.

DESIGN FOR PITCHERS.

Specification forming part of Design No. 7,504, dated June 30, 1874; application filed April 27, 1874.
 [Term of Patent 7 years.]

To all whom it may concern:

Be it known that we, JAMES S. ATTERBURY and THOMAS B. ATTERBURY, of Pittsburg, county of Allegheny and State of Pennsylvania, have invented a Design for Hollow Glassware, of which the following is a specification:

The nature of our design is fully represented in the accompanying photographic illustration, to which reference is made.

In the drawing we have represented a mug or pitcher with our design wrought upon it, but we propose to use this design upon all articles of glassware to which it may be applicable.

The outer surface of the body of the mug is ornamented with raised interwoven splints A, after the style of basket-work, except that the splints on each side of the article shown are

run into or terminated in an ornament, B. At the base and top of the splint-work are ornaments *a b*, as shown, and beyond these ornaments the article is finished with plain surfaces *c d*.

It may not be essential to finish the article with the precise style of ornaments *a* and *b*, nor to make the surfaces *c* and *d* plain.

What we claim is—

The design consisting of the splint-work A and ornament B, for hollow glassware, as herein described and shown.

JAMES S. ATTERBURY.
 THOS. B. ATTERBURY.
